COUPLER AND YOKE ASSEMBLY

Harry H. Wolfe, Columbus, Ohio, assignor to The
Buckeye Steel Castings Company, Columbus,
Ohio

Application December 7, 1948, Serial No. 63,899

7 Claims. (Cl. 213—69)

1

The present invention relates to draft attachments for railway vehicles and more specifically pertains to the structure of the coupler and the yoke for railway cars wherein a horizontally disposed key is employed for connecting these elements of the draft appliance.

One type of coupler which has been a standard device in the railway art includes the use of a swivel yoke employed in association with a twin cushion draft gear and designed for use with a swivel shank coupler. In freight service, when there are occasions for heavy pushing of the cars there is a tendency for the cars connected with swivel shank couplers to jack-knife after passing beyond cross-overs and the cars tend to remain in the jack-knifed position on the straight track until the pushing forces are relieved. When the cars are in such angular or askew positions, and in rounding a curve, additional lateral forces are encountered which tend to derail the cars.

One of the objects of the present invention is to provide a yoke and coupler organization which may be employed in association with a cushion draft gear assembly and so constructed that an angling movement of the coupler is permitted and at the same time to provide a draft attachment which avoids the tendency of the cars to jack-knife in pusher service.

A more detailed object of the invention is to provide a horizontal keyed yoke and coupler combination wherein the coupler is provided with a rigid shank having a flat butt end thereon which, in cooperation with other elements of the draft gear, tends to straighten or align the cars after they move onto a straight track even during the application of heavy forces in buff.

A still further object of the invention is to provide a coupler which does not develop any tendency of the cars to jack-knife after they have passed beyond a cross-over in the tracks and during pushing service and to provide the coupler with a flat rear butt end so that the pressure applied during buffing forces tends to keep the coupler aligned with respect to longitudinal center of the car and to further provide a coupler assembly wherein the objections of wear on the horizontal draft key may be removed by turning the key over for further service.

Other and further objects and features of the invention will be more apparent as the present disclosure proceeds and upon consideration of the accompanying drawings and the following detailed description wherein an exemplary embodiment of the invention is disclosed.

2

In the drawings:

Fig. 1 is a diagrammatic plan view showing the tendency of the cars to jack-knife when pushing forces are applied through swivel shank couplers.

Fig. 2 is a similar diagrammatic view illustrating the manner in which the buffing forces of rigid shank couplers tend to align the cars on straight tracks.

Fig. 3 is a plan view partly in horizontal section showing a draft attachment embodying the invention.

Fig. 4 is a side elevational view of the coupler and yoke structure shown in Fig. 3 with some parts in section.

Fig. 5 is a plan view showing the front draft lugs and portions of the rear draft lug in section.

A standard swivel type shank coupler is diagrammatically illustrated in Fig. 1 which is employed in connection with a swivel type yoke for use in connection with a twin cushion draft gear. In heavy pusher service as encountered on certain railroads there is a tendency for cars to jack-knife after passing a cross-over in the tracks and to stay in this position on straight tracks until the pushing forces are relieved. The approximate angular position which the cars take when jack-knifed is illustrated in Fig. 1. When the cars are in this position and round a curve, additional lateral forces are encountered which tend to derail the cars. It will be further observed from a consideration of Fig. 1 that the lateral force developed during pusher service is in a direction to jack-knife the cars and to keep them out of line on a straight track due to the buffing forces.

The present invention is directed to a coupler having a rigid shank provided with a flat rear butt end, and this structure is such that the lateral component of the forces through the coupler due to the buffing forces is in such a direction as to align the cars on a straight track.

This feature is illustrated in Fig. 2 where the buffing forces are applied at opposite corners of the flat rear butt ends of the couplers to thus tend to keep the couplers centered with reference to the longitudinal center of the cars and to align the cars on a straight track even though the forces are heavy during pusher service.

A draft attachment embodying the present invention is shown in Figs. 3, 4 and 5 wherein the coupler shank is represented at 10. The shank of the coupler is provided with a flat butt end 11 and accordingly corresponds to the rear end face of the coupler shank shown in Fig. 2. The rear flat butt end surface 11 of the coupler shank

is adapted to engage and bear against a front follower 12. The front follower 12 is of conventional construction and is formed as a separate block shaped element. The front follower is interposed between a front draft gear 36 and front draft lugs 15. The coupler shank is provided with a key slot 14 which is elongated and horizontally disposed as shown in dotted lines in Fig. 4.

The draft appliance includes a yoke 16. The yoke is provided with key slots 18 in both forwardly extending nose portions 20. These slots 18 are also of elongated cross-sectional dimensions and horizontally arranged as shown in Fig. 4. A key 19 extends through the slots 18 in the yoke and through the slot 14 in the coupler shank. In the pulling position of the coupler structure the key 19 bears against the front ends 21 of the slots 18 in the nose portions 20 of the yoke. A distinct clearance is provided in the yoke key slots 18 back of the key 19 to allow for a limited amount of angling for the key in the yoke and for the further purpose of allowing the coupler to move rearwardly a limited amount without the rear edge 22 of the key contacting the rear ends of the slots 18 in the yoke structure.

A lug 26 is provided at the top of the coupler shank 10 projecting upwardly therefrom. A similar lug 27 is provided on the lower surface of the coupler shank projecting downwardly therefrom. Each of these lugs 26 and 27 is provided with a hemi-cylindrical surface 28 and the purpose thereof will be more apparent as the present disclosure proceeds.

The yoke 16 is provided with buffering surfaces adapted to be engaged by the arcuate surfaces of the lugs 26 and 27. One of these buffering surfaces is provided at the top of the yoke and is represented at 31 in Figs. 3 and 5. It will be noted that this buffering surface 31 is hemi-cylindrical shaped and is of substantially the same radius as the arcuate surface 28 on the lug 26. It will be further observed that in the pulling position the curved surface 28 is spaced from the arcuate buffering surface 31. A similar arcuate surface 32 is provided on the lower portion of the yoke and adapted to be engaged by the hemi-cylindrical surface provided on the lug 27. The space between the arcuate surface 28 and the curved buffering surface 31 and the space between the hemi-cylindrical surface on the lug 27 and the correspondingly shaped buffering surface 32 on the yoke below the coupler shank are of such dimensions and the parts so shaped as to allow the coupler shank to swivel its full amount in the yoke 16.

When a draft appliance embodying the features herein described is placed in pusher service the forces developed in buff are transmitted rearwardly through the coupler shank 10, and compress the cushion draft gear represented at 36 until the lugs 26 and 27 contact the buffering surfaces 31 and 32 respectively. Thereafter, further buffering forces are taken through the yoke straps 38 and 39 which are connected to a yoke butt 41 and through a rear draft gear 42 to the car structure. The rear draft gear 42 is of the cushion type and this draft gear is interposed between the yoke butt 41 and a rear follower 44. The rear follower 44 is of a conventional construction and is formed as a separate block shaped element. The rear follower is arranged between the rear end of the cushioned draft gear 42 and rear draft lugs 45. The rear draft lugs 45 are attached to the sill structure of the car.

During the application of buffering forces the front draft gear 36 is compressed to a limited extent by the initial rearward movement of the coupler shank 10 and the follower 12 is moved backwardly relative to the yoke 16. Such compression of the front draft gear 36 is arrested when the lugs 26 and 27 engage the buffering surfaces 31 and 32 on the yoke. This limited relative rear movement of the coupler shank is made possible by the dimensions of the key slots 18 in the nose portions 20 of the yoke and the space between the lug 26 and the arcuate buffering surface 31 and the space between the lug 27 and the buffering surface 32. Such compression of the front draft gear 36 provides a reaction force applied forwardly against the front follower 12. The front follower is in flat engagement with the rear butt end 11 of the coupler shank and accordingly tends to maintain the coupler stem in alignment with the longitudinal center of the car. In the event that there is a horizontal angling movement of the coupler during the application of buffering strains a corner of the butt end 11 will tend to push the front follower 12 further rearwardly and additionally compress the front draft gear 36. Additional reacting forces are then applied against the butt end 11 tending to restore the coupler shank to a center position and to avoid jack-knifing of the car. The rearward movement of the coupler shank 10 relative to the yoke is arrested after a predetermined movement thereof and when the lugs 26 and 27 engage the buffering surfaces 31 and 32 on the yoke. The buffering forces are then transmitted through the yoke straps 38 and 39 to the yoke butt 41. The pushing forces are then transmitted through the rear cushion draft gear 42 onto the rear follower 44 and applied to the rear draft lugs 45. During the application of pulling forces the rear end 46 of the coupler key slot 14 contacts the key 19 which then engages the front ends 21 of the key slots 18 in the yoke nose portions 20 and thereby transmits the load through the yoke straps 38 and 39 and the yoke butt 41 onto the front draft gear 36. The pulling load is then applied to the front follower 12 and onto the front draft lugs 15 and thence to the car through the sill structure. The coupler herein shown and described provides for angling movement of the coupler but avoids the disadvantages of a swivel connection between the coupler and the yoke and thereby avoids a tendency of the cars to jack-knife after they have passed beyond a cross-over in the tracks. The pressure of the flat butt end of the coupler shank on the draft gear tends to keep the coupler centered in relation to the longitudinal center line of the car. It will be further observed that the horizontal draft key 19 upon pronounced wear thereof may be removed and inverted so as to present an edge surface which will restore the coupler parts to substantially new condition.

While the invention has been described with reference to specific structural features and with regard to a particular general organization it is to be understood that changes may be made in the parts and that various alterations may be made in the assembly. Such changes and other modifications may be made without departing from the spirit and scope of the invention as set forth in the appended claims.

What I claim and desire to secure by Letters Patent is:

1. In a railway draft appliance, a coupler shank having a horizontally disposed key slot there- 75 through, a yoke, nose portions on the yoke having

horizontally aligned slots therein, a butt end on the coupler shank arranged substantially at right angles to the axis thereof, a key extending through the slots in the yoke nose portions and through the slot in the coupler shank, yoke straps forming a part of the yoke, a lug projecting from the coupler shank approximately at right angles to the axis thereof, a second lug projecting from the coupler shank in an opposite direction substantially at right angles to the axis thereof, a buffering surface carried by the yoke adjacent one of said lugs but spaced therefrom, a second buffering surface carried by the yoke adjacent the other lug but spaced therefrom, said slots in the nose portions of the yoke being of greater dimensions measured horizontally than the horizontal dimension of the key, a front follower arranged in flat engagement with the butt end of the coupler shank, a yoke butt connecting the yoke straps, a resilient draft gear interposed between the front follower and the yoke butt, and a resilient draft gear arranged rearwardly of the yoke butt.

2. In a railway draft appliance, a coupler shank having a horizontally disposed key slot therethrough, a yoke, nose portions on the yoke having horizontally aligned slots therein, a flat butt end on the coupler shank, a key extending through the slots in the yoke nose portions and through the slot in the coupler shank, yoke straps forming a part of the yoke, a lug having an arcuate surface projecting upwardly from the coupler shank, a second lug having an arcuate surface thereon projecting downwardly from the coupler shank, an arcuate buffering surface carried by the yoke adjacent one of said lugs but spaced therefrom, a second arcuate buffering surface carried by the yoke adjacent the other lug but spaced therefrom, said slots in the nose portions of the yoke being of greater dimensions measured horizontally than the horizontal dimension of the key, a front follower arranged in flat engagement with the butt end of the coupler shank, a yoke butt carried by the yoke straps, a resilient draft gear interposed between the front follower and the yoke butt, and a draft gear arranged rearwardly of and engaging the yoke butt.

3. In a railway draft appliance, a coupler shank having a horizontally disposed key slot therethrough a yoke having horizontally aligned slots therein, a flat rear butt end on the coupler shank, a key extending through the slots in the yoke and through the slot in the coupler shank, yoke straps forming a part of the yoke, a lug projecting from the coupler shank approximately at right angles to the axis thereof, a convex surface on said lug, a second lug projecting from the coupler shank in an opposite direction substantially at right angles to the axis thereof, a convex surface on said second lug, a concave buffering surface carried by the yoke adjacent the convex surface of the first lug but spaced therefrom, a second concave buffering surface carried by the yoke adjacent the convex surface of the second lug but spaced therefrom, said slots in the yoke being of greater dimensions measured horizontally than the horizontal dimension of the key, a front follower arranged in engagement with the butt end of the coupler shank, a yoke butt carried by the yoke straps, a resilient draft gear interposed between the front follower and the yoke butt, and a draft gear arranged rearwardly of and engaging the yoke butt.

4. In a railway draft appliance, a coupler shank, a rear butt end on the coupler shank arranged in a plane substantially at right angles

to a longitudinal center of the coupler shank, a front follower in flat engagement with said butt end, a yoke including a yoke butt, a resilient front draft gear interposed between the yoke butt and the front follower, lost motion means connecting the yoke to the coupler shank whereby the front draft gear is compressed upon initial rearward movement of the coupler shank relative to the yoke to provide a reaction force for centering the coupler shank, a buffering surface carried by said yoke, a lug on the coupler shank for engaging said buffering surface after a predetermined rearward movement of the coupler shank relative to the yoke, and a resilient rear draft gear abutting the yoke butt and positioned rearwardly thereof for transmitting buffering forces to a sill structure after said lug engages said buffering surface.

5. In a railway draft appliance, a coupler shank, a rear butt end surface of the coupler shank arranged in a plane substantially at right angles to a longitudinal center of the coupler shank, a front follower in flat engagement with said butt end surface, a yoke including a yoke butt, a resilient front draft gear interposed between the yoke butt and the front follower, means connecting the yoke to the coupler shank for limited rearward movement of the coupler shank relative to the yoke, a buffering surface carried by the yoke, a second buffering surface carried by the yoke, means on the coupler shank for engaging said buffering surfaces during said limited rearward movement of the coupler shank relative to the yoke whereby said butt end surface moves the front follower rearwardly to compress the front draft gear to a limited extent, a resilient rear draft gear abutting the yoke butt and arranged rearwardly thereof, and means for transmitting buffering forces imposed on the rear draft gear to a sill structure for a railway car.

40 6. In a railway draft appliance, a coupler shank, a rear butt end on the coupler shank arranged in a plane substantially at right angles to a longitudinal center of the coupler shank, a front follower in flat engagement with said butt end, a yoke including a yoke butt, a resilient front draft gear between the yoke butt and the front follower urging the front follower forwardly, means connecting the yoke to the coupler shank for limited rearward movement of the coupler shank relative to the yoke and for limited horizontal angling of the coupler shank relative to the yoke, buffering surfaces carried by said yoke, means on the coupler shank for engaging said buffering surfaces during said limited rearward movement of the coupler shank relative to the yoke whereby the butt end surface on the coupler shank moves the front follower rearwardly to compress the front draft gear, and a resilient rear draft gear engaging the yoke butt and arranged rearwardly thereof.

7. In a railway draft appliance, a coupler shank, a rear butt end on the coupler shank arranged in a plane substantially at right angles to a longitudinal center thereof, a front follower in flat engagement with said butt end, a yoke including a yoke butt, nose portions on said yoke, a resilient front draft gear interposed between the yoke butt and the front follower urging the front follower forwardly, a horizontally disposed key extending through a slot in the coupler shank and through slots in said nose portions, said slots being of such dimensions measured horizontally to allow limited rearward movement of the coupler shank relative to the yoke and to allow for horizontal angling of the coupler shank whereby the butt end on the

coupler shank moves the front follower rearwardly to compress the front gear upon initial rearward movement of the coupler shank to thereby set up reaction forces against the butt end on the coupler shank, buffering surfaces carried by the yoke, and lugs on the coupler shank for engaging said buffering surfaces to limit rearward movement of the coupler shank relative to the yoke.
